CLAIM

An ornamental design for a toothbrush holder, as shown and described.

DESCRIPTION

FIG. 1 is a front right perspective view of toothbrush holder showing our new design;

FIG. 2 is a front elevation view thereof; the rear elevation view being identical;

FIG. 3 is a top plan view thereof;

FIG. 4 is a bottom plan view thereof; and,

FIG. 5 is a left side elevation view thereof; the right side elevation view being identical.

The broken lines showing a faucet and toothbrushes are for the purpose of illustrating environment of use and form no part of the claimed design.
